UNITED STATES PATENT OFFICE.

BERN JASSEN, OF BROOKLYN, NEW YORK.

DESIGN FOR AN AUTOMOBILE WIND DEFLECTOR.

Application filed July 25, 1924. Serial No. 10,255. Term of patent 14 years.

To all whom it may concern:

Be it known that BERN JASSEN, a citizen of the United States, and resident of the city of New York, in the county of Kings and State of New York, has invented a new, original, and ornamental Design for Automobile Wind Deflectors, of which the following is a specification, reference being had to the accompanying drawing, forming part thereof, in which,

Figure 1 is a view in perspective of a

wind deflector embodying my new design.

Fig. 2 is a front elevational view of the deflector.

Fig. 3 is a transverse sectional view taken along the line 3—3 of Fig. 2.

I claim:

The ornamental design for an automobile wind deflector as shown.

Dated New York city, July 22, 1924.

BERN JASSEN.
